CLAIM

The ornamental design for a vehicle trailer, as shown and described.

DESCRIPTION

FIG. 1 is a top, rear and left side perspective view of a vehicle trailer, showing my new design.

FIG. 2 is a right-hand side perspective view thereof.

FIG. 3 is a rear perspective view thereof.

FIG. 4 is a top plan view thereof.

FIG. 5 is a bottom plan view thereof; and,

FIG. 6 is a front perspective view thereof.

The left-hand side of the vehicle trailer is a mirror image of the right-hand side depicted in FIG. 2.

The broken line showing of a vehicle trailer are for environmental purposes only, and form no part of the claimed design.
